UNITED STATES PATENT OFFICE.

WILLIAM H. UPTON, OF CAMDEN, NEW JERSEY.

DESIGN FOR A BADGE.

SPECIFICATION forming part of Design No. 20,212, dated October 21, 1890.

Application filed July 15, 1890. Serial No. 358,838. Term of patent 7 years.

To all whom it may concern:

Be it known that I, WILLIAM H. UPTON, a citizen of the United States, and a resident of Camden, Camden county, New Jersey, have 5 invented an improved Design for a Badge, of which the following is a specification.

My design for a badge is fully illustrated in the accompanying drawing, the figure of which represents a face view of the badge.

10 The leading features of the design are the cross-bar and shield, the ribbon and emblem suspended from the cross-bar, and the medallion suspended from the ribbon.

A is the cross-bar on which is a shield B. 15 On the upper portion of the shield is a ribbon on which is to be placed the name of the order. In the three corners of the shield are the letters F, L, and C, and in the center of the shield is a cornucopia showing money

20 flowing therefrom.

Suspended from the cross-bar is a ribbon C, and suspended from the ribbon is a medallion

D, on which is the figure of a woman and a child, with the standing figure of a man protecting the woman and child with a shield. 25 Encircling the figures is a foliated band tied at the base by a ribbon.

Suspended from the lower portion of the shield B is the emblem E, representing two gavels crossed at the center and tied near 30 their upper edges by clasped hands. This emblem is backed with an arrow and a bow, although in some instances the arrow and bow are dispensed with.

35 I claim—

The design for a badge, as shown and described.

In testimony whereof I have signed my name to this specification in the presence of two subscribing witnesses.

WILLIAM H. UPTON.
